UNITED STATES PATENT OFFICE.

JOHN E. SHAFFER, OF TULSA, OKLAHOMA.

GAUGE COCK.

Application filed May 3, 1926. Serial No. 106,228.

My invention relates to gauge cocks and more particularly to gauge cocks and provision for raising the cocks; and the object is to provide improved gauge cocks and improved means for operating the gauge cocks so that a person at any ordinary location below the gauge cock can raise the cock for testing the amount of water in the boiler, this invention being an improvement on the gauge cock shown in the patent granted to me on March 11, 1924, No. 1,486,162. Other objects and advantages will be fully explained in the following description and the invention will be more particularly pointed out in the claims.

Reference is had to the accompanying drawings which form a part of this application.

Fig. 1 is a side elevation of the cock provided with the handle lifting device, and showing in dotted outline the position of the valve operating means when the gauge cock is opened.

Fig. 2 is a side elevation of the gauge cock, showing the opposite side of the cock from that shown in Fig. 1.

Fig. 3 is a detail view of the valve, being an inner face view.

Fig. 4 is a side elevation of the same.

Fig. 5 is a longitudinal cross section of the valve and handle.

Fig. 6 is a broken sectional view, showing the valve construction.

Similar characters of reference are used to indicate the same parts throughout the several views.

The drawings show a steam discharge nozzle 1 provided with a steam passage 2. A handle 3 has a valve chamber 4 therein which is cylindrical in form and the handle has a slot 5 which extends to and communicates with the chamber 4 through a slot 6 in the part of the handle which surrounds the valve 7. The slot 6 is elongated to permit the swinging of the handle 3 relative to the nozzle 1, so that the nozzle will be engaged by the valve 7. The discharge nozzle 1 has an upstanding crane member 8 which projects through the slot 5 and serves as a bearing for anchoring the handle 3 to the nozzle 1 by a pivotal connection, a cotter pin 9 forming the connection.

The valve used herein is a composite valve, having a flanged head 10 of metal or composition metal and a reduced cylindrical body 11 and a cylindrical fibre composition valve

member 7 which is mounted on the body 11. The valve member is preferably made of hardened fibrous material. The cylindrical portion of the valve including parts 11 and 7 constitute the bearing member of the valve to be engaged by the nozzle tip 15. The valve is revolvable in its chamber by loosening the nut 13 which is secured to the bolt 12 and normally bears against the valve member. 60 The valve member 7 may be secured to the cylindrical extension 11 by lugs 14 struck from the member 11 and bent outwardly into cavities in the end of the valve member 7. The valve member 7 rests normally against 70 the tip 15 of the nozzle member 1. When the peripheral surface of the valve member becomes worn where the nozzle tip 15 bears against the valve member, the nut 13 may be loosened and the valve turned slightly to 75 bring an unworn portion against the tip 15. This may be continued until the entire peripheral surface of the valve has been used.

The gauge cock is provided with means for lifting the handle for testing the water level 80 or the amount of water in a boiler from positions below the gauge cock. A chain 16 is connected to the handle 3 and may be extended through the crane member 8 and down to the position below so that a person on a 85 lower floor may test the water in the boiler without having to go up to the boiler. The bearing surface 17 in the crane 8 should be curved, as shown in Figs. 1, 2, and 5 so that the chain 16 will move back and forth with 90 as little friction as possible.

What I claim is,—

1. A gauge cock comprising a handle provided with a cylindrical valve cavity therein and having a slot in the operative end thereof and an elongated slot opening into said cavity, a cylindrical valve mounted in said cavity and provided with a flanged head bearing against the outside of said handle, a bolt rigid with said handle and projected through said valve, a nut for binding said valve rigid with said bolt, a steam discharge nozzle adapted to project into said elongated slot against said valve, and provided with an upstanding crane occupying the slot in the end of said handle and provided with an opening therethrough, and a chain connected to said handle and projected through the opening in said crane. 95

2. A gauge cock comprising a handle provided with a cylindrical valve cavity therein and provided with a slot in the operative end 100

105

110

leading to said cavity, a steam discharge nozzle adapted to project into said slot and into said cavity, means for pivotally connecting said handle to said discharge nozzle, a bolt 5 in said cavity rigid with said handle, a valve composed of a combined flanged head for engaging said handle and a bearing member consisting of a reduced central cylindrical extension in the central portion of said cavity and a hard fibre cylindrical nozzle engag-

ing member mounted on said extension; a nut engaging the end of said bolt for binding said valve rigid therewith, a bearing crane on said nozzle, and a chain operatively connected to said handle and extended over said crane for 15 lifting said handle.

In testimony whereof, I set my hand, this 31 day of March, 1926.

JOHN E. SHAFFER.
